UNITED STATES PATENT OFFICE.

FRANK A. RADCLIFFE, OF CLEVELAND, OHIO.

DESIGN FOR A BATH-TUB TRAP.

SPECIFICATION forming part of Design No. 35,536, dated December 31, 1901.

Application filed July 27, 1901. Serial No. 69,994. Term of patent 7 years.

To all whom it may concern:

Be it known that I, FRANK A. RADCLIFFE, a citizen of the United States, and a resident of Cleveland, in the county of Cuyahoga and State of Ohio, have invented a new and original Design for Bath-Tub Traps, of which the following is a specification, reference being had to the accompanying drawings, forming part thereof.

The essential and characteristic feature of my design consists of a closed receptacle having two openings, one in its top and one in its side near its top, from which annular casings or tubes extend outwardly at right angles to each other.

In the accompanying drawings, Figure I represents a side elevation of my design. Fig. II represents a perspective view. Fig. III represents a plan view.

Referring to the drawings, *a* represents the outer shell or body portion of my design. This body portion is spherical in form, except near its top, where it is slightly reduced to

form a neck portion *a'*, which is capped by a flat top *a²*. A number of lugs or ears *b*, *b'*, *b²*, *b³* are arranged at equal intervals on the outer surface of the top *a²*. An opening *c* is formed in the side of the body portion *a* near the top, and from the edges of this opening an annular casing or tube *c'* extends outwardly a short distance beyond the body portion. Another opening *d* is formed in the center of the top *a²*, and from the edges of this opening an annular casing or tube *d'* extends upwardly at a right angle to the tube *c'*.

Having described my invention, what I claim as new, and desire to secure by Letters Patent, is—

The design for a bath-tub trap, substantially as herein shown and described.

Signed by me at Cleveland, Ohio, this 18th day of July, 1901.

FRANK A. RADCLIFFE.
